United States Patent Office

Des. 186,286
Patented Oct. 6, 1959

186,286

COUNTER SCALE

Henry De S. Lauve, Grosse Pointe, Mich., assignor to Fairbanks, Morse & Co., Chicago, Ill., a corporation of Illinois

Application June 12, 1958, Serial No. 51,311

Term of patent 14 years

(Cl. D52—10)

Fig. 1

Fig. 3

Fig. 1 is a perspective view of a counter scale showing my new design;

Fig. 2 is a front elevational view of said counter scale with the scale beam removed.

Fig. 3 is a side elevational view of said counter scale with the scale beam removed.

The dominant features of the design reside in the portion shown in full lines.

I claim:

The ornamental design for a counter scale, as shown and described.
